[57] **CLAIM**

The ornamental design for a travel game employing clipboard with individual magnetized alphabet squares, as shown and described.

DESCRIPTION

FIG. 1 is a front elevational view of the travel game employing clipboard with individual magnetized alphabet squares showing my new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and ,

FIG. 7 is an exploded isometric view thereof, with four of the magnetized squares shown removed from the clipboard for ease of illustration.
